UNITED STATES PATENT OFFICE.

SAMUEL SMILEY, JR., OF CINCINNATI, OHIO, ASSIGNOR TO THE GLOBE-WERNICKE COMPANY, OF CINCINNATI, OHIO, A CORPORATION OF OHIO.

LOOSE-SHEET BINDER.

Application filed March 14, 1923. Serial No. 625,102.

To all whom it may concern:

Be it known that I, SAMUEL SMILEY, Jr., a citizen of the United States, and residing at Cincinnati, in the county of Hamilton and State of Ohio, have invented a new and useful Improvement in Loose-Sheet Binders, of which the following specification is a full disclosure.

This invention relates generally to filing devices and particularly to filing folders, generally comprising a protective cover of foldable material and providing means secured thereon for retaining correspondence sheets, or sheets containing similar data, within the folder.

A troublesome feature relative to said folders is the tearing of the folder material at points of attachment with the fastening devices used for securing the sheets to the folder, thus necessitating a frequent renewal of the folder cover.

An object of the invention is to eliminate the necessity for such frequent renewal, by reinforcing the material of the cover at points of attachment of the sheet-retaining or fastening device.

Another object of the invention is to provide sheet-retaining means detachably engaged with the reinforcing means, said 30 means in the form of a paper-retaining clip or fastener, the same being engaged in such a manner as to be conveniently replaced when broken, as by frequent bending.

Other objects and certain advantages 35 will be more fully set forth in the description of the accompanying drawings forming a part of this application, in which:

Figure 1 is an inner face view of a correspondence folder having a reinforcing member and detachable clip or fastener applied thereto.

Figure 2 is an enlarged detail plan view 40 of the fastener attached to the sheet, corresponding to Fig. 1.

Figure 3 is a section on line 3—3, of Fig. 2, showing the sheets traversed by the up-standing prongs of a clip, or sheet-retaining element and showing in dot-and-dash lines said prongs bent to sheet-retaining 45 position.

Figure 4 is a cross section of the device on line 4—4, of Fig. 2.

The clip holding and reinforcing member 50 1 is preferably made from a sheet of

bendable material, notched at its corners, 55 to provide when folded, a flattened tubular or slotted tubular structure of substantially elliptical cross-sectional configuration having on one side two inwardly directed slots 3 at relatively opposite ends, (see Fig. 2). 60 The edges 2 of the blank are spaced apart as shown to provide a relatively narrow slot 5. The reinforcing member 1 may also be made from tubular stock flattened to present a substantially elliptical cross section and the end slots formed in any suitable manner. The slots 3 are of sufficient width to provide space for the insertion and attachment of fastening devices 6 for holding the body 1 to the sheet 7, the fastening 70 devices being thus countersunk with relation to the upper face of the member 1, so that the sheets may lie flatly against said upper face. The inner extremities of the slots provide shoulders 8 as stops to lock 75 the metallic strip or clip member 9, of greater length than the reinforcing member 1, which member 9 is inserted lengthwise of the body or member 1, and the projecting ends, preferably of equal length, 80 thereafter turned upwardly at a right angle to a vertical position and against the shoulders, as shown in Fig. 3, to lock said clip against lateral displacement and to provide tangs or prongs over which openings 85 10, preferably provided in the sheets 15, are engaged.

After a sufficient number of papers, either one or more, have been thus placed, the prongs are bent downwardly thereagainst, 90 as shown in dot-and-dash lines at 8^a in Fig. 3, to prevent disengagement.

In other words, I provide a loose leaf binder clip which comprises a slotted tubular member adapted to be secured to 95 a folder sheet. This tubular member is notched at its opposite ends on its slotted side in order to receive and confine the opposite ends of a strip. This strip extends through the tubular member and is bent to 100 provide these tongue ends extending from the notches and adapted to engage and bind a plurality of loose sheets.

This construction provides reinforcement of the material of the folder at the point of attachment of the paper-retaining means, and further provides for the convenient attachment, removal and renewal of 105

the clip or fastener when the same is broken as by frequent bending. Provision is also made for countersinking the rivets, or similar devices, used for fastening the tubular member to the sheets, relative to the upper surface of said member, to prevent interference of the rivets or other suitable fastening devices with the sheets.

Having described my invention, I claim:

10 1. A loose sheet binder clip, comprising a slotted tubular member, adapted to be secured to a folder sheet, said member at its opposite ends and slotted side being notched inwardly for receiving and confining the opposite tongue ends of a strip engaged within said slotted tubular member, and a strip extended through said slotted tubular member and bent to provide tongue ends respectively engaged in and extending from said notches, providing means for engaging through and binding loose sheets.

2. A loose sheet binder clip, comprising a tubular member, adapted to be secured to a folder sheet, said member at its opposite ends having aligned notches for receiving and confining the opposite tongue ends of a strip engaged within said tubular member, and a strip extended through said tubular member and bent to provide tongue ends respectively engaged in and extending from said notches, providing means for engaging through and binding loose sheets.

In witness whereof, I hereunto subscribe my name, as attested by the two subscribing witnesses.

SAMUEL SMILEY, JR.
